UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

TRIMMING DEVICE FOR SEWING-MACHINES.

1,048,204.

Specification of Letters Patent. Patented Dec. 24, 1912.

Original application filed July 26, 1904, Serial No. 218,192. Divided and this application filed August 10, 1905. Serial No. 273,574.

To all whom it may concern:

Be it known that I, LANSING ONDERDONK, a citizen of the United States, residing at New York, in the county of New York, State of New York, have invented certain new and useful Improvements in Trimming Devices for Sewing-Machines, of which the following is a description, reference being had to the accompanying drawing, and to the letters and figures of reference marked thereon.

This application is a division of my application filed July 26th, 1904, Serial No. 218,192, patented June 28, 1910, No. 962,974, and relates to improvements in the trimming device used on the machine illustrated in such application, and to certain improvements relating to the construction of the cloth plate in connection with said trimmer, and to the provision of a guide for diverting 20 the trimmed off strip.

The invention is illustrated in the accompanying drawings, in which,

Figure 1 is a front elevation of a sewing machine embodying my invention; Fig. 2 is a detailed plan of the throat plate; Fig. 3 is a detailed view of the upper trimmer-supporting arms; Fig. 4 is a perspective view of the inner side of the cloth plate cover and strip-diverting guide; Fig. 5 is a sectional view on the line 5—5, Fig. 4; Figs. 6 and 7 are detail views of the strip-diverting guide with the improved device for preventing the strip from passing beneath the cloth plate of the machine; Fig. 8 is a side view 35 of the cloth plate, illustrating the holding device for the lower cutting device; Fig. 9 is a sectional view through the cloth plate showing the means for adjusting the lower trimmer member laterally; Fig. 10 is a detail 40 view of the adjusting device; Fig. 11 is a detail of the pin support for the lower blade holder; Fig. 12 is a perspective view of the lower trimmer parts in detail; Fig. 13 is a detail perspective, showing the cloth plate 45 extension, throat plate, and lower trimmer; Fig. 14 is a perspective view of the cloth plate and diverting guide; Fig. 15 is a sectional detail view showing the relation of the trimmer and its support to the overhanging arm; Fig. 16 is a sectional view 50 through the cover plate showing the spring pin 40.

In these drawings, I use the reference numerals of the corresponding parts re-

ferred to in the above entitled application, 55 and as shown in Fig. 2 the throat plate 29 is provided with the regular slots for the feed dog, a space 30 for the lower knife blade of the trimmer, and a tongue 31 over which the stitches are formed, and which 60 serves to support the edge of the fabric. The throat plate also has a cut out portion 32 for the passage of the stitched edge of the material, in order not to stretch or distort the said edge. The cloth plate 33 is attached 65 to the bed casting of the machine in the usual manner, being held in position by screws.

To the front end is pivoted by means of a screw 34, an extension 35, which projects to 70 the right of the body portion, and forms a rest 36 for the hand of the operator, or to which a guide may be conveniently attached. This extension 35 is held in operative position by means of a spring 37 attached to the 75 apron or downward extension of the cloth plate. When in operative position, the extension is in the position shown in Fig. 1.

I have attached to this machine a hinged cover 38, secured to the bed casting of the 80 machine along its bottom edge, by screws 39, and held in place at the top by a spring pin 40, see Fig. 16, inserted in the top of the central bearing lug for the main shaft, and registering with the hole 41 in cover 38. 85 The cover 38 carries on its outer face a guide 42 for diverting the strip severed from the body fabric, toward the front of the machine and away from its operating parts. This diverting guide is normally spring pressed 90 forward by means of the spring 43 pressing against the bracket 44, secured to the inner side of the cover 38 by screws 45, which pass through slots 46 in said cover.

The diverting guide is shown in two different forms in Fig. 1, and Figs. 6 and 7. That shown in Figs. 6 and 7 is the preferred form and is made with a surface obliquely inclined toward the rear of the machine, which conforms to the direction of travel 95 given the loop spreader, and allows the ready deflecting of the trimmed off strip away from the machine. The upright portion 47 of the diverting guide is arranged in line with the back edge of the trimmer 100 blades to allow them to completely sever the fabric before the deflection of the cut off strip is commenced. I find this an essential 105

feature, as the partially severed fabric refuses to be readily diverted, causing improper feeding of the material. On the operative edge of the strip-diverting guide 5 there is provided a vertically extending projection 48, which serves to close up the space between the inclined edge 49 of the guide, and the exposed parts of the trimmer and machine, and prevents the trimmed off strip 10 from passing into the working parts of the machine.

It will be noted by reference to Fig. 14 that a space is provided between the cloth plate extension 36 and the diverting guide 42, for the passage of the strip severed from the body fabric, and diverted by the diverting guide 42. The trimming device as illustrated, is similar in many respects to that shown in a patent granted to R. G. Woodward and myself, November 27, 1906, #837,106. The upper trimming member 50, is carried by a lever 51 pivoted to a bracket supported by the bed of the machine. This lever 51 may be coupled to an oscillating 25 arm 57 by means of a latch lever 68. The arm 67 is oscillated from the main shaft 69 by means of a link 70, and a suitable eccentric. The overhanging arm H and needle lever L are directly above the forward end 30 of the cutter supporting lever 51. The cutter 50 as clearly shown in Fig. 15 is curved in the arc of a circle and is so arranged in the supporting lever that it projects forward away from the overhanging arm. The object 35 of this curving of the knife is, so that when the cutter carrying lever 51 is released from the operating arm 67 and moved to inoperative position as shown in dotted lines, Fig. 15, said cutter will not strike the 40 overhanging arm. This construction also admits of making the upper knife of greater length, thus admitting of its longer use before being ground away so far that it is no longer useful.

45 The holder 51 is provided with a slot 52 conforming with the curvature of the edges of the knife, to adjustably hold the same in position.

The stationary part of the trimmer is 50 mounted on the under side of the cloth plate, and capable of being adjusted laterally with respect to the line of feed, to vary the width of the seam, and the distance from the edge of the material to the line of needle punctures into the material.

The support 53 is formed with a recess 55 for the lower stationary blade 54. Said stationary blade is held in place by a block, attached to the support 53 by a screw 56. 60 Said support 53 is mounted in slide-ways underneath the work plate, and is retained in position by a screw 57 passing through a slot in the apron of the work plate, and engaging the support 53 as shown in Figs. 8 and 9. This support 53 is adjusted later-

ally by means of a screw 58 having its head 59 projecting outside of the work plate apron, and having a cut-out portion 60 in engagement with the collar 61, secured by screws 62 to the apron of the cloth plate, and its end 63 entering the threaded hole 64 in the support. When it is desired to adjust the trimmer, the screw 57 is loosened and the screw 58 turned, which moves the support in or out, depending on which way the screw 75 is turned.

Turning the screw 58 from front to back adjusts the support 53 to the right. It will be noted that as the stationary member of the trimmer is moved laterally, the guide for diverting the trimmed off strip is also correspondingly moved.

In order to more firmly support the lower trimming blade, I have provided the supporting pin 65 shown in detail in Fig. 11 of the drawing. Said pin 65 is threaded in the base of the machine and has a flat upper end against which the support 53 rests. This pin does not in any manner interfere with the adjustments of the trimmer support, but 90 does take the downward thrust caused by the upper blade. The pin may be adjusted by turning the same in its threaded bearing and is held in its adjusted position by a set screw 66.

In the rear of the trimmer, I have provided an edge guide 70, which as shown in the present embodiment of my invention, is secured to the work support and projects vertically above the same. This edge guide is substantially in the trimming line, and the purpose of said edge guide, is to prevent the material from being stitched, after it passes the trimming mechanism, and the stitching mechanism from being deflected laterally into the trimmer operating mechanism. The stitched edge will pass along said vertical edge guide, and be held in proper position upon the work support. Said edge guide may be supported in any manner, the essential feature being that said edge guide shall project above the work support and be so located relative to the trimmer operating mechanism, as to prevent the material being operated upon, from getting into the operating parts.

Having thus described my invention, what I claim as new and desire to secure by Letters Patent, is—

1. The combination with a work support, 120 an overhanging arm, a needle bar reciprocating on said overhanging arm, a needle carried thereby, complementary stitch-forming mechanism co-operating with said needle, and a trimming mechanism including a trimming blade, a lever carrying said trimming blade, said lever being pivoted in the rear of the overhanging arm and extending forward underneath said arm, means for vibrating said lever, said trimming blade 125 130

being formed on the arc of a circle, extending forward and away from the overhanging arm, whereby said lever may be swung upward on its pivot, without the trimming blade striking the overhanging arm, said lever having means for supporting said trimming blade whereby said blade may be adjusted in the direction of its length.

2. A trimming mechanism for sewing machines including in combination, a work support, an upper trimming member, means for operating the same, a lower stationary trimming member, a support for said lower member located beneath the work support and on the side of said lower trimming member opposite the upper trimming member, a screw threaded centrally into the end of said support, means for preventing longitudinal movement of said screw relative to the work support, whereby the trimmer support may be adjusted, and means for holding said trimmer support in its adjusted positions.

3. In a sewing machine including in combination, a trimmer, comprising an upper movable member, a lower stationary member coöperating therewith, a support having a projecting arm carrying said lower member, and an independent adjustable vertical member for supporting the free end of said arm.

4. A sewing machine including in combination a trimmer comprising an upper movable member, a lower stationary member coöperating therewith, a support having a projecting arm carrying said lower member, means for adjusting said support whereby said lower member is adjusted relative to

said movable member, and an independent adjustable vertical support on which said arm rests.

5. A sewing machine including in combination, a work support, stitch-forming mechanism, a trimming mechanism comprising a movable member, an arm located substantially in rear of the stitching point and supporting said movable member, means for vibrating said arm, and a vertical guide located in the rear of the stitching point and substantially in the trimming line, whereby the edge of the material after it passes the trimmer and stitch forming mechanism, may be guided in the proper direction, and kept away from the movable arm.

6. In a sewing machine for forming over-edge stitches, a work support and an overhanging arm, a trimmer comprising an upper movable member and a lower stationary member coöperating therewith, said trimmer severing the fabric in advance of the stitch-forming mechanism, said upper trimming member including an arm and a blade, the latter being formed in the arc of a circle, extending forward and away from the overhanging arm, whereby said trimmer may be brought close to the needle without striking the overhanging arm, said arm having means for supporting said trimming blade, whereby said blade may be adjusted longitudinally.

In testimony whereof I affix my signature, in presence of two witnesses.

LANSING ONDERDONK.
